(57) **CLAIM**

The ornamental design for a deck light, as shown and described.

DESCRIPTION

FIG. 1 is a perspective view of a deck light embodying the design of the present invention.

FIG. 2 is a front side elevational view of the deck light illustrated in FIG. 1.

FIG. 3 is a back side elevational view of the deck light illustrated in FIG. 1.

FIG. 4 is a right side elevational view of the deck light illustrated in FIG. 1.

FIG. 5 is a left side elevational view of the deck light illustrated in FIG. 1.

FIG. 6 is a top view of the deck light illustrated in FIG. 1; and, FIG. 7 is a bottom view of the deck light illustrated in FIG. 1. The broken lines shown on the drawings depict portions of the deck light that form no part of the claimed design.

1 Claim, 6 Drawing Sheets
